UNITED STATES PATENT OFFICE.

JAMES F. FREEMAN, OF LAWRENCE, ASSIGNOR TO JAMES W. BROOKS,
TRUSTEE, OF CAMBRIDGE, MASSACHUSETTS.

EDGE-TRIMMING CUTTER.

SPECIFICATION forming part of Letters Patent No. 443,434, dated December 23, 1890.

Application filed July 15, 1889. Serial No. 317,527. (No model.)

To all whom it may concern:

Be it known that I, JAMES F. FREEMAN, of Lawrence, county of Essex, State of Massachusetts, have invented an Improvement in Edge-Trimming Cutters, of which the following description, in connection with the accompanying drawings, is a specification, like letters on the drawings representing like parts.

10 This invention is an improvement upon that represented in United States Patent No. 402,375, dated April 30, 1889. The patent referred to contains a series of circular cutters connected by screws to a disk secured to a 15 rotating shaft, the said cutters having each a single cutting-edge.

In the invention at present under consideration the disk-like cutters are secured to studs provided at their inner ends with gear-teeth, each stud having bearing in a stud-plate fixed to the cutter-shaft, and also, preferably, having an additional bearing in a loose bearing-ring. The gear-teeth of the said studs engage a pinion secured to a chambered guard loose on the cutter-shaft, so that as the plate carrying the said studs is rotated in unison with the cutter-shaft the said gear-teeth, being in engagement with the said pinion there at rest with the said guard, gives 30 to the cutters a planetary motion.

My invention consists, essentially, in an edge-trimming cutter containing a series of rotary cutters and means to impart to them a planetary motion, substantially as will be 35 described.

Figure 1 of the drawings is a section taken through part of the cutter-shaft and cutter thereon in the line *y*, Fig. 2. Fig. 2 is a left-hand end view of the cutter shown in Fig. 1. Fig. 3 is a view with the face-plate removed, the cutter-shaft being in section in the line *x*. Fig. 4 is a section in the line *x'*, looking toward the right. Fig. 5 is a detail showing one of the cutters, and Fig. 6 shows the bearing-ring detached.

The cutter-shaft *a* has a shoulder *a'*, against which bears the inner end of the hub of a chambered guard or cup *b*, mounted loosely upon a reduced part of the said cutter-shaft.

50 The hub of this guard at its end nearest the

outer end of the cutter-shaft has attached to it a gear *b'*.

The guard or cup *b* receives within it loosely at its face a stud-plate *c*, (see Figs. 1 and 3,) having a hub *c'*, fitted to a reduced part *a'* 55 of the cutter-shaft, the said plate coming against the shoulder *2*, where a key or projection 10 enters a notch in the said plate to key it to the shaft *a*, and this cup-like guard also receives within it loosely a smaller bearing-ring *c'*, (see Figs. 1 and 6,) provided with holes 12, the said stud-plate *c* and ring *c'* being held together by a series of screws *c*², herein shown as three in number, the said screws between the said stud-plate and ring 60 passing through washers *c*³, so that when the screws are turned in to hold the said plate and ring together they will not act upon and bind the gears *d*, connected with or forming part of the studs *d'*, to which by set-screws 70 *d*² are fixed the cutters *e*, shown as having each two cutting lips or edges, but which may have but one cutting-lip, as in the said patent.

The studs *d'* at opposite sides of the gear-teeth *d* are cylindrical and take bearing in holes in the said stud-plate and bearing-ring, respectively. The cutter-shaft has also mounted upon its reduced end a rand-guide or face-plate *f*, having a lip of usual shape to 75 enter a rand-crease, said plate having apertures therein to receive the set-screws, whereby access may be had to the studs of the cutters without removing the plate.

The rotation of the shaft *a* and the attached rand-guide and stud-plate while the guard *b* and gear *b'* stand still causes the cutters *e* to be carried in a circular path about the center of the stationary gear *b'*, the speed of rotation being that of the cutter-shaft, and 80 at the same time the gear-teeth *d* of the studs *d'*, carrying the said cutters, by reason of their engagement with the gear *b'*, will cause the studs and cutters to be rotated independently about their own axes in the plate 85 *c* and ring *c'*, or, in other words, the cutters *e* will have a planetary movement, thus permitting them to cut the leather very rapidly, the double cutting-edges 56 yet further increasing the rapidity of the cutting opera- 90 95 100

tion. By giving the cutters a planetary movement it is possible to provide each cutter with more than one cutting lip or edge and enable the cutter to do a greater amount 5 of work.

I claim—

1. A rotary edge-trimming cutter containing a series of rotary cutters and means to impart to them a planetary motion, combined 10 with a face-plate *f*, having a lip to enter a rand-crease and apertures to receive the studs upon which said cutters are mounted, substantially as described.

2. In an edge-trimming cutter for leather-work, the rotating shaft, the chambered disk loose thereon and provided with a gear *b'*, the rand-guide, the stud-plate, and the geared 15 studs therein in engagement with the said

gear *b'*, combined with the cutters connected to the said studs, substantially as described. 20

3. In an edge-trimming cutter for leather-work, the rotating shaft, the chambered disk loose thereon and provided with a gear *b'*, the rand-guide, the stud-plate, and the geared 25 studs therein in engagement with the said gear *b'*, combined with the cutters connected to the said studs, the said cutters having two cutting-lips, substantially as described.

In testimony whereof I have signed my name to this specification in the presence of 30 two subscribing witnesses.

JAMES F. FREEMAN.
